UNITED STATES PATENT OFFICE.

FRED C. HANNAHS, OF KENOSHA, WISCONSIN, ASSIGNOR OF ONE-HALF TO
JOHNSON A. JACKSON, OF SAME PLACE.

DESIGN FOR A CRIB OR CRADLE-BODY.

SPECIFICATION forming part of Design No. 21,530, dated May 10, 1892.

Application filed March 18, 1892. Serial No. 425,482. Term of patent 7 years.

To all whom it may concern:

Be it known that I, FRED C. HANNAHS, of Kenosha, in the county of Kenosha and State of Wisconsin, have invented a new and useful Design for a Crib, Cradle-Body, or Similar Article of Furniture, of which the following is a description, reference being had to the accompanying drawing, which is a part of this specification.

10 The figure of the drawing represents a perspective view of my design for a crib, cradle-body, or similar article of furniture.

15 The leading feature of my design consists in a crib, cradle-body, or similar article of furniture provided with a certain ornamentation composed of filling for the spaces between the rails, comprising, primarily, spindles having balls or globes arranged thereon, and the general appearance and style also 20 produced by the peculiar configuration of the head and foot posts.

25 The letters A A indicate the head-posts, and B B the foot-posts, of the form and configuration clearly shown in the drawing, the principal characteristic of which being the arrangement thereon at suitable points of series of annular corrugations, with an ornamental formation between the corrugations.

30 The letters C C indicate the bottom rails, and D D the top rails, which are connected by vertical spindles E, said spindles having arranged thereon balls or globes F, having

their surfaces so arranged as to produce the effect of a central collar or ridge. It will be seen that a series of three of the vertical 35 spindles are connected together by transverse strips G, the ends of said strips entering balls or sockets F. These several vertical spindles, constituting sets of three, are connected together by transverse strips H, also entering or 40 engaging other balls F, arranged medially of the outside vertical strips of said sets of three. Both the head and foot rails are connected near their lower ends by transverse braces I, between which and the bottom rails are arranged 45 vertical spindles J, also provided medially with the balls F, said balls in turn being shown as connected by transverse rods K. The head-rails are shown as connected near their upper ends by a transverse brace L, between 50 which and the top rail D are arranged vertical spindles M, also provided medially with the balls F, which, however, in this instance are not shown as connected by transverse rods.

55 I claim—

The design for a crib, cradle-body, or similar article of furniture, substantially as herein shown and described.

In testimony whereof I affix my signature in presence of two witnesses.

FRED C. HANNAHS.
